US00D926588S

(12) **United States Design Patent** (10) Patent No.: **US D926,588 S**
(45) Date of Patent: ** Aug. 3, 2021

(54) **BAG**

(71) Applicant: **AVERY DENNISON RETAIL INFORMATION SERVICES, LLC**,
Mentor, OH (US)

(72) Inventors: **Caroline Hughes**, Edwalton (GB);
Daniel Kennedy, Northampton (GB)

(73) Assignee: **Avery Dennison Retail Information Services, LLC**, Mentor, OH (US)

(**) Term: **15 Years**

(21) Appl. No.: **29/697,235**

(22) Filed: **Jul. 5, 2019**

(51) LOC (13) Cl. **09-05**

(52) U.S. Cl.

USPC **D9/702**

(57) **CLAIM**

The ornamental design for a bag, as shown and described.

DESCRIPTION

FIG. 1 is an isometric view of a bag with a display hook inserted, showing our design; and

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
